COOLED INJECTION NOZZLE

Karl Lorenz, Stuttgart, Germany; vested in the
Alien Property CustodianApplication April 5, 1940, Serial No. 328,131
In Germany April 28, 1939

3 Claims. (Cl. 299—107.6)

This invention relates to a cooled injection nozzle, particularly for internal combustion engines, whose spraying end is surrounded by a cooling jacket so as to form between the jacket and the body of the nozzle a hollow space for the reception of a coolant.

The invention has for its object to insure effective cooling involving the supply of relatively large amounts of coolant within a restricted space, and this object is attained by having only a narrow blunt portion of a recessed section of the body of the nozzle, interrupted by a coolant feed slot, contact with the inner face of the cooling jacket.

One embodiment of the invention is illustrated in the accompanying drawing, in which

Figure 1 is a longitudinal section of a nozzle according to the invention on the line I—I, of Fig. 2;

Fig. 2, a cross section on the line II—II, of Fig. 1;

Fig. 3, a longitudinal section of the body of the nozzle on the line III—III, of Fig. 2;

Fig. 4, a cross section of the body of the nozzle on the line IV—IV, of Fig. 1; and

Fig. 5, a side view of the body of the nozzle in the direction of the arrow V in Fig. 1, with the cooling jacket shown in section.

1 is a nozzle holder whose end face 2 connects with the body of a nozzle 3 having a longitudinal bore provided with a needle 4 which is pressed upon its seat 5 by a spring 5a. Fuel passes through a bore, not visible, in the nozzle holder 1 into a channel 7 of the member 3, thence through an annular space 8, 9 to the seat 5, lifts the needle 4 when the pressure of an injection pump, not shown, has sufficiently increased to overcome the action of the spring 5a, and is finally sprayed through holes 10.

Near the spray holes 10 the nozzle member 3 is firmly connected, for instance by soldering, with one end of a cooling jacket 11. The other end 12 of the jacket 11 has the form of a flange which by a cap nut 13 is forced into sealing engagement with a shoulder 14 of the nozzle member 3 pressed by the same nut 13 against the end face 2 of the holder 1, dowel pins 21 securing the member 3 in position relative to the holder 1, as indicated in Fig. 2.

The section of the nozzle member 3 covered by the cooling jacket 11 is recessed, and its cross section has approximately the oval form shown in Fig. 4, so that a hollow space 15 for the reception of a coolant is provided. The blunt side 16 of the nozzle member 3 contacts with the inner wall of

the jacket 11 and contains a groove 17 which through a channel 18 is connected with a coolant supplying bore 19 of the shoulder 14 and whose inclined end portion 20 extends into the hollow space 15. The coolant is discharged through a channel 22 which commences above the hollow space 15 and leads through a bore, not visible, in the holder 1 to a coolant return piping, not shown. The channel 22 is so arranged that the coolant fed to the hollow space 15 through the groove 17, 20 must flow around the nozzle member 3 before it leaves the hollow space 15.

What is claimed is:

1. A cooled injection nozzle for internal combustion engines, comprising a body member having a lower recessed portion, a cooling jacket surrounding said lower recessed portion of the body member to form a hollow space for the reception of a coolant, a portion of said body member being substantially oval in cross-section with three arcuate surfaces forming sides, one of said sides comprising a narrow blunt portion, said body member contacting and forming a seal with the inner face of said jacket over the entire height of the hollow space only at said narrow blunt portion thereof, and a groove in said narrow blunt portion of the body member for supplying coolant.

2. A cooled injection nozzle for internal combustion engines, comprising a nozzle body and a circular tubular cooling jacket surrounding its fuel outlet end, a portion of said nozzle body being substantially oval in cross-section with three arcuate surfaces forming sides, two of said sides being spaced from the circular inner wall of said cooling jacket and the third side bearing against and forming a seal with said circular inner wall and with its arcuate surface complementary to said circular inner wall whereby said nozzle body forms a partition extending longitudinally of said cooling jacket, and a passage provided in said nozzle body adjacent the third side thereof and opening into the space between the nozzle body and cooling jacket adjacent the fuel outlet end of the nozzle body for supplying cooling fluid to said space.

3. A cooled injection nozzle for internal combustion engines, comprising a body member having a lower recessed portion and a portion of enlarged diameter above the recessed portion to form a shoulder on the fuel inlet side of the body member, said enlarged portion having a coolant-conducting bore, said recessed portion having an oval cross-section with three arcuate surfaces forming sides, one of said sides comprising a nar-

row blunt portion having a longitudinal groove arranged to communicate with the coolant-conducting bore in the enlarged portion of the body member and having an opening extending through one wall only of the groove at the lower end, a cooling jacket surrounding the lower recessed portion of the body member to form therewith a hollow space for the reception of a coolant, said jacket fitting tightly against and forming a

5 seal with the outer face only of the said narrow blunt portion over the entire height of the hollow space, said jacket having its upper end held tightly against the shoulder on the body member to form a seal therewith, said longitudinal groove being connected at its lower end with the hollow space through said opening in the wall of the groove.

KARL LORENZ.
